[57] ABSTRACT

A closure means provided when operated to interrupt air communication into expandible means such as hoses inserted in grooves in a reeling-up drum used to retain the winding core of for instance paper rolls during the winding-on operation. Preferably, the closure means consists of a resilient body arranged, when actuated by an axially displaceable pressure rod to effect closure or exposure of channels leading to said hoses.

REELING-UP DRUM

BACKGROUND OF THE INVENTION

When sheet-like materials in the form of webs are to be reeled-on or off in a working machine of some kind, for instance in the case of paper webs in printing presses, the roll which usually is provided with an axial winding sleeve is securely attached on a drive shaft having pneumatically expansible means urging pressure elements on the spindle or drum radially outwards into engagement with the inner circumference of the sleeve. The central body of the reeling-up drum is formed with grooves of T-shaped cross-sectional configuration, each one of these grooves housing a rubber hose which, when inflated, urge a longitudinally extending pressure element inserted in the groove radially outwards into engagement with the winding sleeve. A roll spindle or drum of this kind possesses a considerable load-bearing capacity.

In principle, the attachment of the roll on the spindle or drum is effected in that the pressure elements are urged with considerable force into the winding sleeve such that the pressure elements fix the roll relative to the longitudinal axis of the reeling-up drum. The larger the air pressure exerted on the rubber hoses, the deeper the embedment of the pressure elements in the winding sleeve. Upon large specific loads on account of heavy roll weights, air will, however, be pressed from the upper rubber hoses to those positioned at a lower level. Upon rotation of the spindle a pumping effect will arise resulting in deterioration of the retainment of the roll and displacement of the roll from the drive shaft centre. In addition, the hoses will rapidly wear out on account of the mechanical stress on them. In the event that leakage should occur on the hoses in the reeling-up drum, the latter of course loses its load-carrying and retaining capacities entirely. To remedy this drawback valves have been suggested, mounted in connecting or junction channels in the reeling-up spindle so as to communicate with the hoses, these valves being normally closed but, upon actuation of operation means, being made to open to enable inflation of the hoses. However, it has proved a complicated task to mount reliably operating closure valves in these junction channels in the reeling-up drum, and in addition, they make the roll spindle considerably more expensive.

SUMMARY OF THE INVENTION

The present invention has for its purpose to remedy this drawback. It is characteristic of the invention that the reeling-up drum comprises a means arranged for movement in said axial channel and adapted upon movement in one direction to close the inner end of all said radial junction channels.

When air has been blown into the various hoses and the junction channels leading to them have been closed off, excellent load-bearing capacity of the reeling-up drum is achieved while at the same time its concentricity is retained in that the air in the upper hoses, instead of being displaced to the lower hoses, is merely further compressed. These features are obtained owing to the simple yet efficient sealing of all junction channels leading to the hoses by means of one single closure means.

BRIEF DESCRIPTION OF THE DRAWINGS

The invention will be further elucidated in the follow-

ing with reference to the accompanying drawings wherein

FIG. 1 is a broken side view of a reeling-up drum, shown partly in longitudinal section, the reeling-up drum being provided with a junction channel leading to one of the hoses as well as with a closure means in accordance with the invention.

FIG. 2 illustrates on an enlarged scale a cross-section through the reeling-up drum along line II-II of FIG. 1, the reeling-up drum pressure elements being in their radially outer position,

FIG. 3 shows a similar cross-sectional view with the pressure elements being in an inoperative position,

FIG. 4 illustrates on an enlarged scale as compared with FIG. 1 a longitudinal section through the right-hand trunnion of the reeling-up drum, the closure means being in operative (closed) position,

FIG. 5 is a similar longitudinal section, the closure means being designed in accordance with a second embodiment and shown in its inoperative (open) position, and

FIG. 6 is a longitudinal section through a further embodiment with the closure means in its open position.

DETAILED DESCRIPTION OF A PREFERRED EMBODIMENT

The central body 2 of the reeling-up drum 1 illustrated in the drawings is formed with three longitudinally extending grooves 3, 4, and 5 each one of which 30 houses a longitudinally extending rail member 6 forming the reeling-up drum pressure elements. Inside the grooves 3, 4, and 5 internally of the rail members 6 are positioned inflatable rubber hoses 7 which, when inflated, function to urge the rail members 6 radially outwards (FIG. 2). At both ends the hoses 7 are sealingly compressed and urged against the bottom of their respective groove 3, 4, or 5 by means of a pressure plate 8 and a screw 9 passing through said plate. A nipple 10 is inserted into one end of each hose. The nipple extends into a radial channel 11 formed in the central body 2. In accordance with the embodiment illustrated, three such channels 11 debouch into one common, axially extending channel 12 which debouches at the outer end of the trunnion 13. Along its inner longitudinal edges each rail member 6 is formed with stopping ribs 14, upon displacement radially outwards of the rail member these ribs will abut against abutment ribs 15 formed at the periphery of the reeling-up drum and engaging in the associated groove.

50 A rod-like pressure member 20 is axially displaceable in the channel 12, said rod having an axial bore 21 debouching via a radial channel 22 in a peripherally extending notch 23 in the rod-like pressure member 20.

In accordance with FIG. 4 a cylindrically formed plug 55 29 of rubber or similar resilient material is arranged at the inner end of the pressure rod 20, said plug being threaded onto an axial prolongation portion 30 of the pressure rod. A washer 31 is axially displaceable on said prolongation portion 30 and by means of a helical spring 32 is urged against the inner end surface of the resilient body 29. This compresses the resilient body 29 somewhat in the axial direction such that it will abut peripherally against the jacket face of the channel 12 closing off the inner end of the junction channels 11.

60 When the pressure rod 20 is displaced inwards against the action of the spring 32 the inner openings of the channels 11 are exposed, it being then possible

to inflate the hoses 7 with pressurized air. The hoses expand and displace the rail member 6 radially outwards into engagement with the winding sleeve 28, for instance a paper roll (not illustrated) which is threaded on the reeling-up drum 1. The air pressure will remain at the same level in all hoses 7 ensuring good centering of the winding sleeve 28 during the reeling-up operation. As soon as the inflation is completed and the pressurized air nozzle (not shown) removed from the outer end of the pressure rod, the rod together with the closure body 29 will be moved under the action of the spring 32 into the closure position illustrated in FIG. 4, in which position the communication between the hoses is interrupted. Of course, it is likewise possible to displace the pressure rod 20 to its various positions by manipulating the sleeve 26 by means of the fingers of one hand.

A simplified embodiment of the invention is illustrated in FIG. 5. In accordance with this embodiment the closure means consists of a cylindrical body 33 made from rubber or a similar resilient material and inserted into the inner end of the channel 12. The diameter of the closure body 33 is slightly less than that of channel 12 whereby air is allowed to pass into the annular gap thus formed between the closure body and the jacket surface of the channel 12. The pressure rod 20' is provided with a threaded portion 34 the external threads of which mate with internal threads 35 at the outer end of the trunnion 13'. When the pressure rod 20' is screwed into the channel 12 the resilient body 33 is compressed and then closes the inner end of the channels 11, thus interrupting the communication between the hoses 7.

In both cases the outer end of the pressure rod may be provided with a non-return valve 36 of a nature permitting sealing against a seat at the occurrence of an internal pressure inside the hoses 7. When the latter are to be evacuated, it is therefore necessary to open the non-return valve in the usual manner.

An improved embodiment of the drum of FIG. 5 providing for simplified inflation of the reeling-up drum is illustrated in FIG. 6. The rod-like pressure member 20" in accordance with this embodiment is provided at one of its ends with a piston 37 and a sealing 43 therefor. The piston is movable in a cylindrical chamber 40 formed in the trunnion 13". At the axially outer side of the piston 37 is positioned a compression spring 38, held between the piston and an end plug 39.

When pressurized air is inserted through a hole 41 in the wall of the chamber 40 by means of an air nozzle 42, the pressure inside the cylindrical chamber 40 rises, urging the piston and its pressure rod 20" to move against the action of the spring 38, thereby relieving the closure body 33 which thus exposes the air intake channels 11. At the same time, air may thus pass through the central bore in the pressure rod 20" and further through the nipples 10 into the hoses 7.

Upon removal of the air nozzle 42 the pressure inside the cylindrical chamber 40 disappears and through the action of the spring 38 the piston 37 together with its pressure rod 20" exerts a pressure on the closure body 33 which then expands and closes the air inlet channels 11.

The embodiments as shown and described are to be regarded as examples only and the closure means to interrupt the connection with the hoses after inflation of the latter may be constructively altered in a variety of

ways within the scope of the appended claims. Opening and interruption of the communication between the hoses may be effected through rotating the rod 20 instead of displacing it radially if the closure means and the inner rod end are designed accordingly.

What I claim is:

1. An improved reeling-up drum of the kind intended to retain the winding sleeve supporting paper rolls and similar material wound onto sleeve-like cores, comprising grooves formed in the reeling-up drum, expandable means in the form of hoses inserted in said grooves, an axial channel formed in one of the two trunnions of said reeling-up drum, junction channels interconnecting said hoses and said axial channel, and a pressure element positioned in each one of said grooves, said hoses being arranged, when inflated by pressurized air supplied through said axial channel and said junction channels, to displace said pressure elements radially outwards into engagement with the inner circumference of said winding sleeve, a body of resilient material displaceable in said reeling-up drum axial channel, and a rod-like pressure member adapted to move and expand said resilient body to effect closure of said junction channel mouths into said axial channel.
2. An improved reeling-up drum as claimed in claim 1 wherein the rod-like pressure member contains an axial air supply channel and which channel debouches at the periphery of said pressure member.
3. An improved reeling-up drum as claimed in claim 1 comprising a non-return valve formed at the outer end of said rod-like pressure member, said non-return valve being adapted to close at the occurrence of an internal excess pressure in said hoses.
4. An improved reeling-up drum as claimed in claim 1 further including spring means, said closure body being arranged to be urged by said rod-like pressure member against the action of spring means and into a position wherein said junction channels are exposed.
5. An improved reeling-up drum of the kind intended to retain the winding sleeve supporting paper rolls and similar material wound onto sleeve-like cores, comprising grooves formed in the reeling-up drum, expandable means in the form of hoses inserted in said grooves, an axial channel formed in one of the two trunnions of said reeling-up drum, junction channels interconnecting said hoses and said axial channel, and a pressure element positioned in each one of said grooves, said hoses being arranged, when inflated by pressurized air supplied through said axial channel and said junction channels, to displace said pressure elements radially outwards into engagement with the inner circumference of said winding sleeve, means displaceable in said reeling-up drum axial channel, said means being arranged upon its displacement in one direction to close the inner end of all said radially extending junction channels, said junction channels, leading to said hoses, departing from said axial channel, said closure means consisting of a body of resilient material inserted into said channel, a rod-like pressure member being provided to expand said resilient body into engagement with and to effect closure of said junction channel mouths into said channel, a chamber formed in said reeling-up drum, a piston provided in said chamber on said rod-like pressure member, a spring means arranged axially outside of said piston in said chamber, said piston being arranged to move axially outwards upon application of pressurized air into said chamber, whereby said closure body

effects exposure of said junction channel mouths, and to move axially inwards through the action of said spring whereby said closure body effects closure of said junction channel mouths.

6. An improved reeling-up drum as claimed in claim 5

5, wherein an air inlet aperture is formed in the wall of said chamber, said air inlet aperture being formed at a point located axially inside of said piston in the axially inner position of displacement of said piston.
